CHANNELING-MACHINE.

1,115,046.

Specification of Letters Patent. Patented Oct. 27, 1914.

Application filed December 24, 1910. Serial No. 599,194.

To all whom it may concern:

Be it known that I, HENRY W. WINTER, a citizen of the United States, residing at Methuen, in the county of Essex and State 5 of Massachusetts, have invented certain Improvements in Channeling-Machines, of which the following description, in connection with the accompanying drawings, is a specification, like reference characters on the 10 drawings indicating like parts in the several figures.

This invention relates to machines for operating upon soles and is herein illustrated as embodied in a channeling machine. In 15 machines of this type the knives require frequent sharpening. Ordinarily at each replacement of the knives after the sharpening operation said knives must be carefully readjusted, and it is only after repeated trials 20 that the cutting edges are brought to just the positions required.

Accordingly one feature of the present invention consists in the provision in a machine of the class described of readily removable knife blocks by which the knives are held and with respect to which they are adjustable. With this construction after 25 a knife has once been adjusted, said knife and its block may be removed from the machine sharpened and replaced without disturbing the vertical, lateral or angular adjustment of said knife. In the case of the channeling knife of the illustrative machine it is necessary in replacing said knife merely 30 to slide the removable knife block along in its holder until the edge of the knife is at a proper distance from the presser foot and then to clamp said block in place. In the case of the grooving knife the procedure is 35 identical except that the grooving knife is brought up close to the rear of the channeling knife. No further adjustments are required, and the machine will then produce a channel and a groove of the same characteristics as were produced before the knives 40 were removed from the machine.

In channeling soles the channel is not cut entirely around the sole but stops short of the rear end thereof, a portion about the 45 heel being left uncut. Hitherto when the knife has reached that point at which it is desired that the channel should end, it has been customary, after the knife and presser devices have been raised from the feed 50 wheel, to pull the sole sharply so as to

cause the knife to break through the channel flap and thus release the sole from the machine. In the present invention, this necessity for forcibly freeing the sole has been obviated by the provision of automatic 60 means for holding the sole from moving upwardly with the knife; and in the illustrated embodiment this result is brought about by providing a spring which acts against the vertically movable carrier in 65 which the knife and presser foot are mounted to urge the presser foot downwardly with respect to the knife. When, therefore, the carrier, and with it the knife, are raised at the end of the channeling operation, the 70 presser foot does not rise during the first part of the upward movement of the carrier with the result that the sole is held down upon the feed wheel for a moment during 75 which the knife in moving upwardly severs the channel flap.

In channeling soles which are formed with a sharp curve at the toe it is necessary that the machine be run comparatively slowly at this point, while along the forepart and 80 shank the channel may be cut much more rapidly. It has, therefore, been customary to provide channeling machines with means for controlling the power applied to the feed mechanism at any given moment; and 85 a very satisfactory device of this nature is the one used in the hand-belt-power machine. In such machines a crank operatively connected with the driving shaft is provided with a friction clutch actuating 90 member, the parts being so constructed and arranged that, when the crank is turned, the members of the friction clutch are pressed together with more or less force according to the force which is being exerted to turn 95 the crank. It sometimes happens, however, that the contour of the soles to be channeled is such that no variation in the speed of the machine is necessary, and in such cases it is desirable that the machine be capable of 100 being actuated continuously at a constant speed.

Accordingly, another feature of this invention consists in the provision in a machine of the class described of a handle movable manually to control the actuation of the feed mechanism and means for automatically disconnecting said handle and for actuating the feed mechanism to feed the sole at a constant speed. And preferably, 110

since a single constant speed would not be most economical for all types of soles, a change speed gearing is interposed between the driving shaft and the feed mechanism whereby the machine may be run continuously at several constant speeds. This change speed device, it should be noted, is also of value with the hand belt power attachment, since it determines the maximum speed at which the machine is then run.

In the operation of machines of this class the grooving knife removes from the sole a slender string of leather, and this string sometimes comes into contact with the channel flap and falls back into the groove from which it was removed so that after the channelling operation it is necessary to lift up a portion of the string and pull it from the groove, and at other times its free end gets between the sole and the feed wheel thereby causing the knives to gouge the sole. In order, then, to prevent the severed string from coming into contact with the flap of the channel and to guide its free end away from said flap and the moving parts of the machine another feature of this invention consists in the provision of a string guide in the form of a trough which may be adjusted angularly with respect to the grooving knife. The form of the string guide lessens the liability of the string to become jammed, and the angular adjustments enable the string guide to be alined with the axis of the tubular grooving knife. This string guide is preferably mounted in the removable block which carries the grooving knife so that once having been adjusted, the knife block may be removed and replaced without disturbing said adjustment.

Another feature of this invention consists in the provision of an expansible guard by which the extent to which the teeth of the feed wheel penetrate the sole may be varied; and a further feature consists in the provision of a knife which may be adjusted laterally as well as angularly with respect to its holder.

These and other features of the invention including certain details of construction and combinations of parts will be described in connection with an illustrative machine and pointed out in the appended claims.

Referring now to the accompanying drawings.—Figure 1 is a front elevation of a machine in which the present invention is embodied; Fig. 2 is a section through the longitudinal center of the machine, certain shafts, studs and bolts being shown in elevation; Fig. 3 is an elevation of the expansible guard for determining the extent to which the teeth of the feed wheel shall penetrate the stock; Fig. 4 is a perspective of the head of the machine and the feed wheel, a presser foot of particular form being shown in place of the usual presser foot and presser

wheel; Fig. 5 is a perspective showing the grooving knife, the string guide, the grooving knife block in which the knife and guide are adjustably mounted and the grooving knife block holder in which the block is held during the operation of the machine; Fig. 6 is a detail perspective of the edge gage and the bearing for the feed wheel shaft; Fig. 7 is a detail perspective of a portion of one of the clutch-actuating mechanisms; and Fig. 8 is a perspective of a portion of a sole which has been operated upon by the illustrative machine, a section having been removed from the extreme forward part in order to show the channel and groove more clearly.

Referring first to Fig. 8, the function of the machine is to cut a channel in a sole so that the channel flap may be turned back to provide for the stitching operation and to cut at the base of said channel a groove to receive the stitches.

Referring now more particularly to Figs. 2 and 4, the head 1 is provided with a cylindrical stem 2 held in a correspondingly shaped split socket in the frame 3 by means of pinch-bolts 5; and slidably mounted in this head is a carrier 7 urged downwardly by a spring 9 the tension of which may be varied by an adjusting screw 11, the extent of downward movement being adjustably limited by a screw bolt 13 the stem of which is slidable in a bore in the head and is threaded into the carrier. In this carrier are mounted the channelling knife 15, the grooving knife 17, and the presser wheel 19 and presser foot 20 (Fig. 1) or the presser foot 21 (Fig. 4) as may be desired. In order to permit the knives to be removed, sharpened and replaced, without the necessity for careful adjustment, the following construction and arrangement of parts is provided, and inasmuch as the parts which support the two knives are substantially identical only the parts which support one of said knives will be described in detail. Referring to Figs. 4 and 5 the grooving knife block holder, indicated at 23, is provided with a yoke, one arm 25 of which is movable toward the other by a screw bolt 27. The arms of the yoke together with the bottom face of the holder form a dove-tailed slot 28 which is adapted to receive a correspondingly shaped grooving knife block 29, the grooving knife being clamped in angular and lateral position with respect to said block by a clamp having upon one end a clamping disk 31 and threaded upon the other end a nut 33. The bore 34 through which the stem of this clamping device passes is enlarged, as shown in Fig. 4, so as to permit lateral adjustment of the knife. It will now be apparent that after the grooving knife has been once angularly and laterally positioned with respect to the block

29 the knife together with its block may be readily removed from the machine and returned to it without disturbing in any way the angular, lateral or vertical adjustment 5 of the grooving knife. The channeling knife 15 has a stock (not shown) provided with two cut-away portions of the usual form to receive two clamping bolts provided with nuts 35, so that said knife may be adjusted angularly and laterally. In the 10 present machine, however, these bolts pass through a block 37 (Fig. 1) similar to the block 29, and this block is adjustably held in a knife block holder 39 by means of a screw bolt 41, the two last named parts corresponding to the grooving knife block holder 23 and the bolt 27.

With the construction thus far described, it will be evident that after loosening the 20 pinch bolts 5 and moving the head angularly in its socket, or preferably removing said head from the machine, the grooving and the channeling knives together with their respective blocks may be removed from the machine, and after having been ground, may be replaced in the machine without disturbing the angular or lateral adjustments with 25 respect to their respective holders. The channeling knife block is merely moved along in the dove-tailed slot in its holder until the edge of the knife is in close proximity to the presser foot and clamped in 30 position and then the grooving knife is similarly moved up to the channel knife and clamped in place. No further adjustments 35 are necessary; and a sole then fed to the machine will have cut in it a channel and groove identical with those which were cut in other soles previously to the removal and 40 replacement of the knives. It should be noted in this connection that the knife blocks are so constructed that they interfere in no way with the grinding operation so that it is not necessary to remove the 45 knife from its block nor to disturb its adjustment with respect thereto.

The channeling knife block holder 39 is held in adjusted position by means of the rod 43 and the nuts 45 and 47 as shown. 50 The grooving knife block holder 23 is provided with a vertical bore 49 which is intersected by a horizontal bore 51. A rod 53 extends into the vertical bore and is threaded into a pin 55 which extends through the 55 horizontal bore and is normally held in contact with the upper wall of said bore by a spring 57. With this construction the grooving knife may be raised independently of the channeling knife, when desired, and 60 in order to provide ready means for such raising, the holder 23 is provided with a socket 59 to receive the end of a lever 61 which may be operated by a treadle rod 63, said lever being pivoted to the carrier. The 65 carrier 7 is slidably mounted upon the head

1 and may be raised against the force of the spring 9 by a second lever 65 which at one end engages said head and at the other is connected with a treadle rod 67.

The feed wheel is fast to a shaft 69 which 70 is mounted in bearings 71 and 73, the bearing 71 being slidably mounted in the frame of the machine and being normally held in the position shown by a spring 75. The outward movement of the bearing is limited by 75 an adjustable stop 77 which is threaded into the frame of the machine and has a head which engages a lug 78 on the bearing. The inward movement of the feed wheel against the force of the spring 75 is adjustably 80 limited by a nut 76. A set screw 80 is threaded through an arm 79 which is pivoted at 81 to the frame of the machine; and this arm has an extension which is connected at one end with a lever 83 the other 85 end of which is connected to a treadle rod 85. With this construction it is possible by depressing the treadle rod 85 at the proper time to vary the distance of the channel from the edge of the sole and to determine 90 the maximum distance by means of the nut 76, a result desirable in the manufacture of shoes having soles which project farther beyond the upper at one portion than at another. 95

The feed wheel preferably comprises a plurality of toothed sections 87 the inner ones of which are so connected with the hub that forward rotation is permitted with respect to said hub but rearward rotation is 100 prevented, this construction facilitating the turning of the soles particularly at the toe. The particular construction of the feed wheel, however, is immaterial so far as this invention is concerned. Whatever the form 105 of wheel it is desirable that the extent to which the teeth enter the leather be capable of being controlled, and in the illustrative machine an expandible guard, best shown in Fig. 3, is provided. This guard comprises 110 segmental sections 89 which are adjustably clamped by means of screws 90 to a member which rotates with the feed wheel, herein shown as the gear 101 the function of which will presently be described. The outlines of 115 the inner edges of these sections form curves which are not concentric with the axis of the hub 91 of the gear 101; and mounted upon said hub is a cam 92 angular movement of which in one direction forces the sections 120 outwardly and in the other direction permits them to be moved inwardly, said cam being held in adjusted position by clamping screws 93 which pass through holes 95 in the gear and are threaded into the cam. As appears 125 from the drawing the countersinks which receive the heads of the screws 90 are of slightly greater diameter than the heads of said screws, and it should be understood that the holes which receive the stems of the 130

screws are similarly of slightly greater diameter than said stems. The extent of adjustment of the sections is very small and does not substantially change the circular 5 outline of the guard.

The edge gage 97 is rotatably mounted upon an upright stud 99 which is carried by the bearing 71 and is rotated from the gear 101 as shown, a bevel gear 103 being pinned 10 to the edge gage.

According to the character of the soles which are to be operated upon it is sometimes desirable to actuate the feed wheel at constant velocity by power and at other 15 times to actuate it at a varying velocity which is under the control of the operator. It is also desirable that means be provided for changing the velocity at which the feed wheel may be run continuously. The mechanism 20 by which these results are made possible will now be described.

A hollow driving shaft 105 is mounted in bearings 107 and 109; and in this shaft are mounted a solid shaft 113 and a slidable key 25 115. The hollow shaft is provided with two diametrically opposite slots 117, and through these slots as well as through a bore in the solid shaft 113 extends a pin 119 by which a friction member 121 is held, the connection 30 being such that rotation of said friction member compels rotation of both the hollow shaft 105 and the solid shaft 113 while at the same time a limited extent of movement of the friction member and solid shaft longitudinally of the hollow shaft is permitted. The friction member 121 is normally held in the position shown by means of a spring 123 and may be moved to the right against the 35 force of the spring into engagement with a friction surface on a driving pulley 125 by means of a cam 127 which is held normally in the position shown by a spring 129 and may be moved angularly by means of a treadle rod 131 which is pivotally connected 40 with a lug 133 on the cam. The driving pulley 125 has firmly driven into its bore a bushing 135 slidable and rotatable on the hollow shaft 105, on the end of which is screwed a conical collar 137; and the movement 45 of the bushing and hence of the collar and pulley toward the right is limited by a nut 139 which is screwed on the hollow shaft 105, said nut being held firmly in adjusted position by means of a lock nut 141. By 50 this construction the normal position of the pulley, and hence its distance from the friction member 121, can be controlled. With the construction thus far described, it will be apparent that depression of the treadle rod 131 will cause continuous rotation of the driving shaft at a uniform velocity. In order to permit operation so as to vary the velocity when desired, an arm 143 the hub 55 144 of which is loosely mounted upon the nuts 139 and 141 is provided with clutch

teeth 145 which coöperate with similar clutch teeth 147 formed upon a collar 149 which is threaded upon the solid shaft 113 and held fast thereto by the nut 151, a spring 153 of less strength than the spring 123 tending normally to separate the clutch teeth on said arm and collar. A crank arm 155 pivoted at 156 to the arm 143 is provided at one end with a handle 157 and at the other with a wedge 159, best shown in Fig. 7, which is 70 adapted to be forced between the hub of the arm 143 and the cam collar 137 and thereby to move the pulley 125 toward the left into engagement with the friction member 121. Thus when the handle 157 is turned by the 80 operator the wedge operates as described above to apply power to the driving shaft 105 thereby relieving the operator of any considerable effort. And this application of power may be delicately graduated by the 85 operator who holds the handle 57 during the rotation of the mechanism so that the speed at which the sole is fed to the knife at any given instant may be controlled. It will be understood that, when the handle is being 90 used, the cam 127 will be in the position shown.

As has been stated above, the machine may be run continuously at constant speed by depressing the treadle rod 131. A single 95 speed, however, would not meet all requirements, and provision is therefore made for several speeds either one of which may be made use of. And to this end three loose gears 161, 163 and 165 are rotatably mounted upon the driving shaft 105, and any one of them may be locked from rotation with respect thereto by the slidable key 115 which is provided with a web 167 arranged to slide in diametrically opposite slots formed in 100 the driving shaft. The bores of the gears are formed with corresponding diametrically opposite grooves which are designed to receive the web 167 of the key 115 when said grooves register with the slots in the 105 driving shaft. It will thus be apparent that after rotating the gears until the grooves register with the slots the key may be moved to lock any selected one of the gears to the driving shaft. And in order to prevent the 110 key from being moved by the vibration of the machine the stem is provided with three sockets 169 which are designed to receive a spring-pressed locking ball 171. The three gears 161, 163 and 165 mesh respectively 115 with three gears 173, 175 and 177 which are fast to the feed wheel shaft 69. As shown, the gear 173 is keyed directly to said shaft and the gears 175 and 177 are keyed to the gear 173; the effect, however, is to 120 compel the shaft 69 to rotate with the gears.

The grooving knife, as will be seen by an inspection of Figs. 2, 4 and 5, is of tubular form; and this knife removes from the sole at the base of the channel a comparatively 125 130

slender string of leather. Frequently this string falls back into the groove from which it was removed so that after the channeling operation it is necessary to lift up a portion 5 of the string and pull it from the groove, or else its free end gets between the sole and the feed wheel thereby causing the knives to gouge the sole. In order to keep the severed string from contact with the flap of 10 the channel and to guide it away from the moving parts of the machine, a string guide, best shown in Figs. 2, 4 and 5, is provided. This string guide comprises a small trough 179 fast to a pin or shank 181 which passes 15 through a bore in the grooving knife block 29 and is acted upon by a set screw 183 by which the trough may be held in adjusted angular and lateral position.

In Figs. 1 and 2, the machine is shown as 20 provided with a freely rotatable presser wheel 19 to contact with the sole at one side of the channel knife and with a presser foot 20 to contact with the sole at a point to the rear of that at which the presser 25 wheel contacts, the object being to hold the sole firmly down upon the feed wheel during the cutting operation and thus insure a channel of uniform depth.

Instead of using the presser wheel and 30 presser foot referred to above, a presser foot 187 of the form shown in Fig. 4 may be used. This foot has a cut-away portion to receive the knife, as shown, a projecting toe 189 being thus formed which contacts with the 35 sole not only at a point in line with the edge of the knife but also at a point in advance of such edge. Although for convenience the foot has been described as having a cut-away portion by which a projecting toe is 40 formed, it might with equal accuracy be said that the presser foot is provided with a projecting toe whereby a recess is formed for the reception of the cutting portion of the knife. A presser foot of this form is a 45 much simpler and more economical form of construction than the presser foot and presser wheel shown in Figs. 1 and 2 and for certain grades of work is very effective. In both cases, however, the presser foot is 50 supported at the end of a rod 191 and is normally held in its lowermost position by a spring 193, the extent of movement of said rod being limited by nuts 195. When, therefore, the head is raised and with it the 55 knife, the spring holds the sole down upon the feed wheel, and the knife, as it is raised, cuts through the channel flap and leaves the stock, the sole being then free to be removed from the machine. In order that the 60 presser foot may be held in raised position during the adjustment of the knife an arm 197, pivoted to the carrier 7, is provided with two inclines 199 which may be forced between the nut 195 which contacts with the 65 carrier 7 and said carrier.

The driving pulley 125 is run continuously by power, and the tension of the belt (not shown) which passes around said pulley may be adjusted by means of a tightener pulley 205 which is held in position by a 70 bolt 207.

In adjusting the machine the head 1 is removed and held in inverted position in a holder which receives the stem 2. The lever 197 is moved to move and hold the presser 75 foot in opposition to the spring 193. The channeling knife holder is adjusted vertically to bring the edge of the knife flush with the operative edge of the presser foot, and the knife is adjusted laterally and angularly with respect to its block 37. The knife 80 block 37 is then adjusted horizontally to bring the edge of the knife as close to the presser foot as possible while still allowing sufficient space to permit the channel flap 85 to pass between the knife and foot. The grooving knife and the string guide are adjusted with respect to the block 29, the holder 23 is adjusted vertically, and the block 90 is adjusted horizontally until the forward portion of the grooving knife is as close to the back of the channel knife as is possible. The lever 197 is moved to the position shown and the head is then returned to the machine 95 and fastened in place by the screw bolts 5.

The operation of the machine is then as follows:—The head is raised to permit a sole to be fed between the presser foot and the feed wheel, after which the head is lowered, the sole being guided and turned 100 by the operator during the channeling and grooving operation. When the channel has been cut to the desired length, the treadle rod 67 is actuated to raise the head. During the first part of this movement the presser 105 foot, owing to the presence of the spring 193, holds the sole firmly down upon the feed wheel while the knife as it rises cuts through the channel flap. In case it is wished to produce an extension edge on the sole, the 110 treadle rod 85 is depressed at the desired location, the maximum extent of said extension edge having been determined beforehand by adjustment of the nut 76. If it is desired to move the key 115 the shaft 105 115 is turned by hand until the gears have reached the proper relative position whereupon the key may be drawn out or pushed in as the case may be, said key being automatically engaged by the spring-pressed ball 12: 171. As has been stated, the machine may be actuated by turning the handle 157 or by depressing the treadle rod 131. In case the operator desires to vary the speed at which different portions of a sole are fed, he may 125 turn the handle 157. As the handle is turned, the crank 155 moves angularly about the pivot 156, so that the wedge 159 is crowded against the collar 137, the pulley 125 moved toward the left and the friction 130

clutch thrown in and kept thrown in as long as sufficient force is being applied to the handle 157, the force necessary being very slight. It should be noted, too, that by 5 varying the pressure between the members of the friction clutch, the angular velocity of the driving shaft 105 is controlled. The operator, therefore, has complete control of the speed at which the sole shall be fed and 10 can vary said speed at will. In case the operator desires to feed the soles at a constant speed, he adjusts the change speed gearing as described above and depresses the treadle rod 131 thereby forcing the member 15 121 into frictional engagement with the pulley 125. The friction member 121 carries with it the solid shaft 113 and consequently the collar 149, the spring 153 acting to prevent movement of the hub of the lever 143 20 longitudinally of the shaft 105. The clutch teeth 145 and 147 are thus disconnected, and the handle 157, crank 155 and lever 143 do not revolve. Longitudinal movement of the shaft 105 is prevented by two collars 209 25 and 211 while end thrust of the parts is taken by two ball bearings 213 and 215.

Having thus described my invention, what I claim and desire to secure by Letters Patent of the United States is:—

30 1. A machine of the class described having a knife and means for advancing a piece of stock thereto in combination with a substantially vertical holder provided at its lower end with a pair of jaws, means for 35 moving one of said jaws toward the other, a knife block by which said knife is held, said block being adapted to be inserted between said jaws from below, and means for holding said knife in adjusted angular position 40 with respect to said block.

2. A machine of the class described having a knife and means for advancing a piece of stock thereto in combination with a substantially vertical holder provided with 45 a substantially horizontal guideway open at its under side, said guideway being formed with a movable wall whereby the width of said guideway may be varied, means for moving said wall, a knife block 50 adapted to be inserted in and removed from said guideway when said wall is in open position and to be held clamped in said guideway when said wall is in closed position, and means for adjustably fastening said knife 55 to said knife block.

3. A machine of the class described having a knife and means including a presser foot for advancing a piece of stock to said knife in combination with a holder provided 60 with an open sided guideway, a block in which said knife is angularly adjustable, said block being removable from the open side of said guideway and slidale in said guideway toward and from said presser foot,

and means for clamping said block in adjusted position in said guideway. 65

4. A machine of the class described having, in combination, a channeling knife, means under the control of the operator for raising said knife, means for feeding a piece 70 of stock to said knife, a presser foot for holding the stock in engagement with said feeding means, and yielding means for urging said foot toward said feeding means whereby, when said knife is raised, it is 75 caused to cut through the surface of said stock.

5. A machine of the class described having, in combination, a channeling knife, means under the control of the operator for raising said knife, means for feeding a piece of stock to said knife, a presser foot continuously in engagement with said stock to press it against said feeding means, and yielding means for urging said foot toward 85 said feeding means.

6. A machine of the class described having a channeling knife, means under control of the operator for raising said knife, a feed wheel, and means for actuating said 90 feed wheel in combination with means for holding the stock down upon the feed wheel during the upward movement of the knife.

7. A machine of the class described having a carrier, a knife rigidly held with respect to said carrier, means under the control of the operator for raising said carrier, a feed wheel and means for actuating said wheel in combination with a presser foot movable with respect to said carrier, a spring 95 normally compressed during the operation 100 of the machine and arranged to move said foot toward said wheel and a stop for limiting the extent of such movement, said stop being arranged to permit the presser foot 105 to approach nearer than the knife to the feed wheel whereby, when the carrier is raised, the knife is first raised and then the presser foot.

8. A machine of the class described having, in combination, a knife, a feed mechanism, means movable manually to control the rotation of said mechanism and means for automatically disconnecting said manually movable means and for applying power 110 to said mechanism. 115

9. A machine of the class described having, in combination, a knife, a feed mechanism, means movable manually to apply variable power to said mechanism and 120 means for automatically disconnecting said manually movable means and for applying constant power to said mechanism.

10. A machine of the class described having, in combination, a knife, a feed wheel, 125 a driving shaft operatively connected with said feed wheel, a continuously rotating member, a handle normally connected with

said shaft whereby said shaft is normally compelled to turn therewith, and means for successively disconnecting said handle from said shaft and for connecting said continuously rotating member with said shaft.

11. A machine of the class described having a knife and means including a toothed feed wheel for advancing stock thereto in combination with an expansible guard for 10 limiting the extent to which the teeth of the wheel penetrate the stock.

12. A machine of the class described having a knife and means including a toothed feed wheel for advancing stock thereto in 15 combination with an expansible guard for limiting the extent to which the teeth of the wheel penetrate the stock, said guard comprising a plurality of sections one face of each of which has the outline of a segment 20 of a circle and a cam mounted on the hub of said wheel and adapted, when rotated, to force said sections outwardly.

13. A machine of the class described having in combination a knife, an edge gage, a 25 gear fast to said gage, a feed wheel shaft, a second gear mounted upon said shaft and meshing with said first named gear, a feed wheel also mounted upon said shaft, an expansible guard located between said wheel 20 and second gear, and means for rotating said shaft.

14. In a machine of the class described the combination with a grooving knife of a 25 string guide angularly adjustable with respect to said knife, and means for holding said string guide in adjusted position.

15. In a machine of the class described the combination with a grooving knife of a 40 string guide in the form of a trough arranged with its open side uppermost and means whereby said string guide may be angularly adjusted with respect to said knife.

16. A machine of the class described having a grooving knife and means for advancing a piece of stock thereto in combination with 45 a block by which said knife is adjustably held, a string guide also adjustably held by said block, and means for removably holding said block in position whereby said block may readily be removed and replaced while 50 maintaining the adjustments of said knife and string guide with respect to said block.

17. A machine of the class described having, in combination, a knife, a feed wheel, means for actuating said feed wheel, a 55 presser foot movable toward and from said wheel, a spring normally maintaining the operative portion of said foot nearer than the knife to the surface of the feed wheel, and means for raising said foot and holding 60 it in raised position.

18. In a machine of the class described the combination with a grooving knife of a 65 string guide angularly and laterally adjustable with respect to said knife and means for holding said string guide in adjusted position.

19. A machine of the class described having a knife and a feed wheel for advancing a piece of stock to said knife in combination 70 with a head by which said knife is carried, a spring-pressed presser foot also carried by said head, a stop arranged to permit said foot to approach nearer than the knife to the feed wheel, and means for raising said 75 foot independently of said knife and for holding it in raised position.

In testimony whereof I have signed my name to this specification in the presence of two subscribing witnesses.

HENRY W. WINTER.

Witnesses:

CHESTER E. ROGERS,
GEORGE W. GATES.
